UNITED STATES PATENT OFFICE

ORVILLE S. HERSHY AND ERNEST J. VAN SICKEL, OF CHICAGO, ILLINOIS, ASSIGNEES,
BY MESNE ASSIGNMENTS, TO OAKES PRODUCTS CORPORATION, OF NORTH CHICAGO,
ILLINOIS, A CORPORATION OF MICHIGAN

DISTRIBUTOR AND LOCK THEREFOR

Application filed November 7, 1928. Serial No. 317,822.

An object of the invention is to provide a distributor for automobile ignition circuits adapted to control the making and breaking of the circuit through the interrupter, the whole being contained in a distributor casing so that external means cannot be used to circumvent said control.

Another object is to provide a remote control for said distributor preferably operated by a lock cylinder.

A further object is to provide a separate flexible control means adapted to be secured at one end to a remote part of the automobile, such as the dash, and at the other to the distributor casing.

A still further object is to provide a control means so arranged as to be likely to render the ignition inoperative if the control of the distributor is tampered with.

These and other objects, as will hereinafter appear, are accomplished by this invention which is fully described in the following specification and shown in the accompanying drawings in which—

Figure 1 is a top plan view of a portion of the distributor showing an interrupter or breaker in closed position;

Fig. 2 is a vertical longitudinal section through a lock associated therewith;

Fig. 3 is a section on line 3—3 of Fig. 2;

Fig. 4 is a partial section on line 4—4 of Fig. 1; and

Fig. 5 is a wiring diagram of an ignition circuit embodying this invention.

This invention is adapted to be used in connection with distributors and interrupters of well known form now used in automobile ignition.

The embodiment illustrated comprises a metal casing 10 adapted to be placed within an insulating housing (not shown) of a distributor and surrounding the usual distributor shaft 11. This distributor which is intended to be used in connection with a six cylinder engine has a hexagonal cam 12 upon which operates a cam follower 13 carried by an interrupter arm 14. The latter is pivotally mounted upon a pin 15 but is insulated therefrom and carries a breaker point 16 which normally makes contact with a breaker

points 17 adjustably carried upon a screw 18, the latter being threaded to a block 19.

The block 19 is connected to a wire 20 with one side of a condenser 21, the other side of the condenser (not shown in detail) being grounded upon the metal casing 10 which, in turn, is grounded on an automobile chassis, as will later be described. The metal casing 10 has an extension 10^a which is hollow and preferably rectangular in form. Within this is located a rectangular sleeve 22, and within this sleeve is a block 23 of insulating material which is grooved to receive a metal plunger 24. This plunger has pieces of insulation 24^a inserted therein. Between these pieces of insulation, however, is a portion 25 adapted to be engaged, when in mid-position as shown in Fig. 1, by a metal spring 26 which is otherwise insulated from the metal casing, and is carried upon an insulating pin 26^a. This spring connects with the arm 14 and serves the double purpose of holding the arm 14 closed so as to normally make contact between the breaker points 16 and 17.

The plunger 24 carries a screw 27 by means of which it is adjustably secured to a wire 28 which passes therethrough and out through a flexible metal conduit 29. This conduit is secured within a metal block 30 which, in turn, is secured within the extension 10^a of the metal casing by means of a drive pin 31 which, when so assembled, is driven firmly in place and sawed or ground off so that it cannot readily be removed.

The wire 28 and its enclosing conduit 29 extend to some convenient point on the automobile frame such as a dash 32 (see Fig. 2), to which it is then secured by means of a lock mechanism which will now be described, and which controls the operation of the plunger 24. The conduit 29 is secured within a block 33 which, in turn, is secured within a tubular member 34 preferably by welding at 35. The tubular member 34 carries at its front end a lock housing 36 within which is a rotatable lock cylinder 37 which is secured to a tubular member 38 within which is located a cam groove 39.

A pin (not shown) carried by a hollow

member 40 operates in the cam slot 39, and the member 40 is prevented from turning by means of a key 41 in a key slot 42 in the member 33. It will thus be seen that as the 5 lock cylinder 37 is turned, the member 40 and wire 28 will be drawn to the left, thereby pulling the plunger 24 in against the action of a spring 43 within the sleeve 22. In the position shown in Fig. 1, electric current will 10 flow through the arm 14, spring 26, plunger 24, and thence through the sleeve 22 and casing 10 to ground. By this arrangement, the operation of the interrupter is not interfered with except to break the circuit leading thereto. The rest of the wiring diagram shown in Fig. 5 will be understood without further explanation, it being illustrative only of a circuit with which this device can 15 be used.

20 The circular portion of the casing 10 has a series of grooves 44 adapted to receive outwardly extending ears 45 on the circular metal cover 46 (see Fig. 4). These pass through openings 47 in the top of the casing 10. These ears and openings are similarly but unequally spaced so that the cover will fit in only one position. This is so because the depending lug 48 (see Fig. 1) will lie in front of the plunger 24. The plunger has a 25 diagonally disposed slot 49 in the upper portion which permits the lug 48 to pass in the unlocked normal position shown. When locked, the plunger is retracted so that the slot 49 is no longer in the path of the lug 48 and the lug strikes the plunger and is 30 stopped. The plunger 24 will then be moved so as to place one of the insulation strips over the contact finger 26 and consequently the primary circuit will be broken and ignition 35 will be stopped. The casing 10 and cover 46 are hardened to prevent their being opened to gain access to the plunger 24.

If the wire is cut in an effort to release the lock, the spring 43 forces the plunger 24 forward to the right of the position shown again 40 breaking contact with the finger 26 and locking the lug 48. The tubular member 34 has two outwardly struck ears 50 to act as abutments for the dash 32, while the end 51 is 45 screw-threaded to receive a nut 52. The members 34 and 36 are drilled to receive a metal pellet 53 which rides by gravity on the lock cylinder 37 which has a flattened portion 54 to receive it. The inside of the nut 52 is cut 50 away by an annular groove 55. When the lock cylinder 37 is in the unlocked position, the groove 54 permits the pellet 53 to drop so that the nut 52 can be unscrewed and the 55 whole removed from the dash or panel 32.

When locked, however, the pellet is forced 60 up into the groove 55 so that the nut cannot be removed.

While we have shown and described but a single embodiment of our invention, it is to 65 be understood that it is capable of many mod-

ifications. Changes, therefore, in the construction and arrangement may be made which do not depart from the spirit and scope of the invention as covered by the appended claims.

We claim:

1. In a distributor, an interrupter, a metal casing for said interrupter, a metal cover for said casing, said casing having a lateral tubular extension, and means operable through said extension for rendering said interrupter inoperative, said means including a spring-operated plunger slideable within said extension and adapted when in a neutral position to render said interrupter operable and when in either its outer position or inner position to render said interrupter inoperative. 70

2. In a distributor, an interrupter and a circuit controlled thereby, a metal casing for said interrupter, a metal cover for said casing, said casing having a lateral tubular extension, and means operable through said extension for rendering said interrupter inoperative, said means including a spring-operated plunger slideable within said extension and adapted when in a neutral position to render said interrupter operable and adapted when in either its outer position or inner position to render said interrupter inoperative by breaking said circuit. 80

3. In a distributor, an interrupter and a circuit controlled thereby, a metal casing for said interrupter, a metal cover for said casing, said casing having a lateral tubular extension, and means operable through said extension for rendering said interrupter inoperative, said means including a spring-operated plunger slideable within said extension and adapted when in the operative position to render said interrupter operable and to render said interrupter inoperative in another position of the plunger by breaking said circuit, said plunger serving to lock said cover on the casing when in a position to break said circuit. 100

4. In a distributor, an interrupter and a circuit controlled thereby, a metal casing for said interrupter, a metal cover for said casing, said casing having a lateral tubular extension, and means operable through said extension for rendering said interrupter inoperative, said means including a spring-operated plunger slideable within said extension and adapted when in the operative position to render said interrupter operable and to render said interrupter inoperative in another position of the plunger by breaking said circuit, said cover having an ear adapted to lie in the path of said plunger, said plunger being cut away to permit said ear to pass when in the operative position of the plunger and to stop the movement of said ear when in an inoperative position of said plunger. 110

5. The device according to claim 2 characterized by said plunger and cover having portions which become engaged when the plunger moves into a position to break said 5 circuit to lock the cover on the casing.

6. In a distributor, an interrupter, a casing for said interrupter, an extension on said casing at right angles to the distributor axis, a plunger shiftable longitudinally within 10 said extension, switch mechanism controlled by said plunger and connected with the interrupter circuit, a spring in said extension tending to shift said plunger to cause it to render the interrupter circuit operative, and 15 means controlled from a remote point for shifting said plunger against the force of said spring to cause said switch to render said circuit ineffective.

7. In a distributor, an interrupter, a casing 20 for said interrupter, a lateral extension on said casing, a plunger shiftable within said extension, switch mechanism controlled by said plunger to control the interrupter circuit, restraining means normally holding said 25 plunger in position to cause said switch mechanism to close the interrupter circuit, and a spring in said extension adapted to shift said plunger to cause said switch mechanism to open said circuit when said restraining 30 means is broken.

8. In a distributor, an interrupter, a casing for said interrupter, an extension on said casing, a plunger slideable in said extension, switch mechanism operable by said plunger 35 for controlling the interrupter circuit, a spring within said extension tending to shift said plunger inwardly, restraining means cooperating with said spring for normally holding said plunger in position to cause the 40 switch mechanism to render said circuit effective, and means for actuating said restraining means to shift said plunger outwardly against the force of said spring to cause the switch mechanism to open said circuit, said 45 spring being free to shift said plunger inwardly past its normal position to cause the switch mechanism to open the circuit when said restraining means is rendered ineffective.

50 In testimony whereof, we have hereunto set our hands this 3 day of November, 1928.

ORVILLE S. HERSHÉY.
ERNEST J. VAN SICKEL.
